UNITED STATES PATENT OFFICE.

WILLIS E. ROYS, OF NEW YORK, N. Y.

CORRUGATED RADIATOR.

SPECIFICATION forming part of Letters Patent No. 794,315, dated July 11, 1905.

Application filed June 14, 1904. Serial No. 212,569.

To all whom it may concern:

Be it known that I, WILLIS E. ROYS, a citizen of the United States, and a resident of the city of New York, Richmond Hill, borough 5 of Queens, in the county of Queens and State of New York, have invented a new and Improved Corrugated Radiator, of which the following is a full, clear, and exact description.

The invention relates to metal radiators for 10 steam-heating; and its object is to provide a radiator that will take up very little room and no floor-space.

My invention hanging on the wall and being made of sheet metal is not so heavy as 15 cast-iron and can be easily fastened to the wall.

The invention consists of novel features and parts and combinations of the same, as will be more fully described hereinafter and then pointed out in the claims.

20 A practical embodiment of the invention is represented in the accompanying drawings, forming a part of this specification, in which similar characters of reference indicate corresponding parts in all the views.

25 Figure 1 is a front elevation of my improved radiator. Fig. 2 is an end elevation of the same, the supporting-pipe being shown in section. Fig. 3 is partly a top plan view and partly a horizontal sectional view of the same; 30 and Fig. 4 is a detail view on a larger scale, being partly a top plan view and partly a horizontal section.

The steam-pipe 1 has a valve 2 and a horizontal connection or portion 3, which is supported at a suitable height above the floor, 35 and is here shown as provided with perforations.

The radiator is made of corrugated sheet metal, the central portion of which is flattened and bent around the pipe 3, the side and top edges of the wall B thus formed being flattened, as at D F, and united together. The corrugations 4 in the front and rear walls and which extend above the pipe 3 form steam- 45 spaces between said walls and increase their superficial area. Steam is discharged from

the said pipe 3 through its perforations or openings into the said steam-spaces. The corrugations of the respective walls register, and said walls are secured together between 50 the corrugations by means of rivets C. On the upper edge of the radiator is placed a cap or rail E, which is preferably of the construction shown, and is attached to a bracket G, which is secured to and projects from the wall. 55 The corrugations in the walls of the radiator besides providing the steam-spaces therein and greatly increasing the superficial areas thereof also greatly strengthen the construction of the radiator. 60

My improved radiator is exceedingly compact, cheap, light, efficient, does not obstruct the floor and enables the floor to be readily cleaned under it.

I claim—

1. In combination with a supporting supply-pipe, a radiator made of sheet metal and having a portion bent around the said supporting supply-pipe, the walls thus formed having their edge portions flattened and united 70 together and their intermediate portions corrugated to form steam-spaces between said walls, a cap on the upper edge of the radiator, and a supporting-bracket attached to said cap. 65

2. A radiator made of sheet metal, doubled 75 to form a cylindrical portion and side walls above said cylindrical portion, said side walls being corrugated to form steam-spaces between them, and a supporting and steam-supply pipe extending through and fitting in said 80 cylindrical portion of the radiator, said pipe having openings to discharge steam into the steam-spaces of the radiator, substantially as described.

3. In combination with a supporting-pipe, 85 a radiator made of sheet metal and having a portion bent around the pipe.

WILLIS E. ROYS.
